(No Model.)

J. M. BAILEY.

BRICK KILN.

No. 430,724.

Patented June 24, 1890.

UNITED STATES PATENT OFFICE.

JOHN M. BAILEY, OF GOODSON, VIRGINIA.

BRICK-KILN.

SPECIFICATION forming part of Letters Patent No. 430,724, dated June 24, 1890.

Application filed October 24, 1889. Serial No. 327,973. (No model.)

To all whom it may concern:

Be it known that I, JOHN M. BAILEY, of Goodson, in the county of Washington and Commonwealth of Virginia, have invented 5 certain new and useful Improvements in Kilns, of which the following description, in connection with the accompanying drawings, is a specification.

The object of the invention is to provide a 10 downdraft-kiln of improved construction for burning bricks, pottery, &c., in which the bricks or other material shall be burned uniformly and thoroughly throughout the entire mass, and in which the waste heat may 15 be utilized for making steam for use in handling the clay, &c.

The invention consists in the construction hereinafter described and claimed.

In the drawings, wherein like letters of reference indicate like parts in the several figures, Figure 1 is a transverse sectional elevation of my improved kiln, and Fig. 2 is a partial longitudinal section of the same on the plane of the dotted line $\alpha\alpha$ of Fig. 1.

25 The outer walls A of the kiln are provided with usual firing-ports B, through which are to be admitted the heat and products of combustion from furnaces, as indicated at the right in Fig. 1, or liquid-fuel burners, as indicated at the left.

30 Within the outer walls and at the base of the kiln are erected two intermediate walls C C, which form the sides of the exit-flue D. Above these intermediate walls and resting upon them, and at their ends being supported in the outer walls, are the transverse tubular floor-girders E E, which are coupled in series, as indicated, and support the perforated floor F of fire-clay, bricks, or other suitable material. At the outer 35 edges of the floor and, it may be, supported by the girders stand the fire-walls G G, perforated as at $g\ g$. It will be seen that the floor extends beyond the planes of the intermediate walls and in such outer portions is perforated, 40 as at ff , as well as in the middle portion over the flue, as at $f'f'$. The walls G G stand at a sufficient distance from the walls A to form flues and combustion-chambers H H, which 45 may be open at the top, and at the bottom as are extended beneath the outer portions of the floor, as at $H'H'$. One end of the series 50 of tubular girders is connected with a steam

drum or boiler K, and the other end with a water-supply L. The connection to the water-supply may be made through a series of longitudinal pipes M and drums N placed in the upper portion of the flue D. The water is thus admitted first to the coolest portion of the boiler thus formed. As the hot air and gases pass into the kiln, they are distributed 55 by the walls G G. Portions pass by the flues H up over the top of the mass of bricks, &c., down through the same, and through the floor and into the exit-flue. Other portions pass through the fire-walls, and so through the 60 bricks and floor into the exit-flue. Still other portions pass by the flues H H' up through the perforations $f\ f'$ and then through the 65 bricks and floor, thereby thoroughly burning the bricks, &c., in the outer lower portions of 70 the mass, where, in kilns heretofore devised, many soft-burned bricks were to be found, no matter how thoroughly burned were the rest of the bricks. As the waste heat passes down through the floor it comes in contact 75 with the tubular girders and with the longitudinal pipes, thereby heating the water contained therein, and furnishing abundance of steam for use in handling the clay, &c., without the expense of a separate boiler. 80

I claim—

1. In a kiln, the combination of outer walls having firing-ports, a perforated floor, transverse tubular girders supporting said floor and connected with a steam-drum, intermediate walls forming a flue, and longitudinal tubes connected with said transverse tubular girders, as and for the purpose described. 85

2. In a downdraft-kiln, the combination of outer walls having firing-ports, transverse tubular girders supported at their ends by said walls, a steam-drum connected with one end of the series of tubular girders, intermediate walls also supporting said girders and forming an exit-flue, longitudinal pipes in said 90 flue connected at one end with the other end of said series of transverse girders, and a water-supply connected with the other end of said longitudinal pipes, as and for the purpose described. 95

JOHN M. BAILEY.
